RAILWAY SWITCH OPERATING APPARATUS

George L. Temple, Rosedale Heights, Pa., assignor
to The Union Switch & Signal Company, Swiss-
vale, Pa., a corporation of Pennsylvania

Application November 20, 1942, Serial No. 466,307

8 Claims. (Cl. 246—291)

My invention relates to railway switch operating apparatus, and particularly to manually controlled switch operating apparatus for switches of the type which are intended to be trailed.

One object of my invention is to provide novel and improved apparatus of the type described including within a single housing manually operable means for throwing the switch to either extreme position and for subsequently yieldingly holding it in either extreme position to which it is thrown, means for locking the switch in one extreme position for facing point moves over the switch and for automatically unlocking it mechanically for trailing moves, and means for preventing objectionable slapping of the points while a train is trailing the switch.

Other objects and characteristic features of my invention will become apparent as the description proceeds.

I shall describe two forms of railway switch operating apparatus embodying my invention, and shall then point out the novel features thereof in claims.

In the accompanying drawings, Fig. 1 is a top plan view showing a railway switch provided with one form of switch operating apparatus embodying my invention. Fig. 2 is an enlarged top view partly in section of the switch operating apparatus shown in Fig. 1. Fig. 3 is a vertical longitudinal sectional view of the apparatus shown in Fig. 2 taken substantially on the line III—III of Fig. 2. Figs. 4 and 5 are views similar to Fig. 2 showing the switch operating apparatus in different operating positions. Fig. 6 is an enlarged right-hand end view of a buffering device D forming part of the apparatus illustrated in Figs. 2, 3, 4 and 5. Figs. 7 and 8 are vertical longitudinal sectional views of the device D shown in Fig. 6 taken on the lines VII—VII and VIII—VIII, respectively, of Fig. 6. Fig. 9 is a sectional view taken on the line IX—IX of Fig. 7. Fig. 10 is a view similar to Fig. 1 showing a railway switch provided with another form of switch operating apparatus embodying my invention. Fig. 11 is an enlarged top view partly in section of the switch operating apparatus shown in Fig. 10. Fig. 12 is a vertical sectional view of the apparatus shown in Fig. 11. Fig. 13 is a fragmentary sectional view showing a portion of the buffering device D forming part of the apparatus illustrated in Figs. 11 and 12. Fig. 14 is a detail view of a portion of the apparatus shown in Figs. 11 and 12. Fig. 15 is a detail sectional view taken on the line XV—XV of Fig. 11.

Similar reference characters refer to similar parts in each of the several views.

Referring first to Fig. 1, the reference character A designates a railway switch comprising, as usual, two fixed rails 1 and 1a and two movable rails 2 and 2a. The fixed rails 1 and 1a are laid on tie plates 3 and are secured to crossties 4 in the usual manner. The movable rails 2 and 2a are fastened together by a front rod 5, a head rod 6, a bridle rod 7, and a tie rod 8, and may be moved into a normal or a reverse position by means of an operating rod 9 which is connected with the head rod 6 through the medium of the usual switch basket 10. When the switch occupies its normal position in which it is shown in Fig. 1, the movable rail 2 engages the fixed rail 1, and the movable rail 2a is spaced a slight distance from the fixed rail 1a. When the switch is reversed, however, the movable rail 2a then engages the fixed rail 1a, and the movable rail 2 is spaced from the fixed rail 1.

Associated with the switch A is a switch operating mechanism B embodying my invention. As here shown, the mechanism B comprises a casing 11 having a main compartment 11a provided with a removable cover 13. A switch actuating shaft 14 is journaled in a vertical bearing 11c provided in the bottom wall of the main compartment 11a, and has fixed thereto on the underside of the casing a removable switch operating arm 14a which is pivotally attached to the free end of the previously described operating rod 9, the parts being so proportioned that rotation of the shaft 14 through an angle of approximately 90° will move the switch between its normal and reverse positions.

The upper end of the shaft 14 is provided with a cam member 15 having a cam surface 15a and a laterally projecting arm 15b. The cam surface 15a cooperates with a roller 16 provided on a crank 17 journaled between plates 18 and 19 secured together at their end and disposed in vertically spaced relation. The plates 18 and 19 comprise a driving member which I shall designate 18—19, and are mounted for longitudinal sliding movement in suitable guides 11d provided in the bottom of the compartment 11b. The upper plate 18 is provided on its upper face with rack teeth 20 which mesh with a pinion gear 22a mounted on a shaft 22. The shaft 22 is square except for a rounded portion at each end, and is journaled at its ends in suitable bearings provided in the opposite side walls of the main compartment 11a. A hand throw lever 21 is fixed to the one outer end of the shaft 22 and

provides means whereby the shaft may at times be rotated to reciprocate the driving member between two extreme positions.

The crank 17 is provided with a second roller 23 which cooperates with a thrust bar 24. The thrust bar 24 is attached to the one side wall of the casing 11 by means of a pair of spaced angularly disposed parallel slotted links 25 and 26, and is operatively connected at one end with a spring rod 27. The spring rod 27 extends through a guideway 28 into a spring compartment 11e formed in one end of the casing 11, and is surrounded within the compartment by a compressed coil spring 31 which constantly urges the spring rod toward the left as viewed in Fig. 2. A nut 33 is screwed onto the inner end of the spring rod, and provides a convenient means whereby the compression of the spring 31 may be readily varied. The parts are so proportioned that in any position to which the driving member 18-19 is moved, the spring 31 will act through the spring rod 27, thrust bar 24, and roller 23 to exert on the crank 17 a force which tends to rotate the crank in a counterclockwise direction as viewed in Fig. 2, and which force is opposed by engagement of the roller 16 with the cam surface 15a of the cam member 15.

The arm 15b of the cam member 15 is connected by means of a link 35 with the piston rod 36 of a buffing device D. This buffing device may have any preferred construction but as here shown (see Figs. 6, 7, 8 and 9) it comprises a cylinder 11f closed at one end by a cylinder head 37 and at the other end by a cylinder head 38. The piston rod 36 extends into the cylinder 11f, through a stuffing box 39, and through a suitable opening 37a in the cylinder head 37 and is fastened to two spaced reciprocable pistons 40 and 41. The cylinder 11f is intended to be filled with a suitable fluid such as oil, and the stuffing box 39 forms a fluid tight joint through which the piston rod may slide.

The wall of the cylinder 11f is provided at its left-hand end with a leak groove 100 and at its right-hand end with a leak groove 101. The function of the grooves 100 and 101 is to permit fluid to flow past the pistons under certain conditions which will be made clear hereinafter.

A reservoir 11g which may also be filled with fluid is formed in the casing 11 directly above the cylinder 11f. The cylinder is constantly connected near its center with this reservoir by means of an opening 42 in the cylinder wall. The cylinder is also connected at its left-hand end with this reservoir through two coaxial ports 43 and 44 (see Fig. 8), and at its right-hand end with the reservoir through two coaxial ports 51 and 52.

The flow of fluid through the ports 43 and 44 is controlled by a poppet valve F comprising a valve member 45 carried by a valve stem 46, and cooperating with a valve seat 43a formed in the end of the port 43. The right-hand end of the valve stem 46 is fluted and extends into the ports 43 and 44, while the left-hand end of the valve stem 46 slides in a guide bearing 47 formed in a plug 48 screwed into a threaded opening in the cylinder head 38. A spring 49 having one end located in an annular recess 50 in the plug 48 to center the spring with respect to the valve stem, engages the valve member 45 and constantly urges the valve member toward the valve seat 43a.

The flow of fluid through the ports 51 and 52 is controlled by a poppet valve G similar to the poppet valve F described hereinbefore. As here-

shown, the poppet valve G comprises a valve member 53 carried by a valve stem 54 and cooperating with a valve seat 52a formed in the end of the port 52. The left-hand end of the valve stem 54 is fluted and extends into the ports 51 and 52, while the right-hand end of the valve stem 54 is adapted to slide in a guide bearing 55 formed in a plug 57. The plug 57 also has formed therein an annular recess 58 which receives one end of a coil spring 59. The other end of the coil spring 59 engages the valve member 53 and constantly urges the valve member 53 toward the valve seat 52a.

The valves F and G are operated by two poppet valves 60 and 61, respectively, which, in turn, are actuated by a cam 62a formed by cutting away a portion of a cam shaft 62, as best seen in Figs. 8 and 9. The tappet 60 is slidably mounted in two lugs 63 projecting upwardly from the wall of the cylinder 11f into the reservoir 11g, and the tappet 61 is likewise mounted in two similar lugs 64. The cam shaft 62 is journaled in two bearings 65 and 66 screwed into the side walls of the cylinder 11f, as best seen in Fig. 9. The outer end of the cam shaft 62 is provided with an arm 62b which is pivotally connected through an adjustable link 67 to a depending portion of a lug 68 provided on one end of the driving member 18-19. The parts are so proportioned that when the driving member occupies its normal position in which it is shown in Fig. 2, the cam 62a is rotated out of engagement with the tappet 60 and into engagement with the tappet 61 so that valve F is closed and valve G is open. When the driving member is rotated to its opposite extreme position in which it is shown in Fig. 5, however, the cam 62a is rotated out of engagement with the tappet 61 and into engagement with the tappet 60.

To facilitate the insertion of fluid into the cylinder 11f, a screw plug 69 is provided in the reservoir 11g as best seen in Fig. 9.

Means are also provided for at times permitting fluid to flow freely from one end of the cylinder 11f to the other, and for at other times retaining fluid in one end of the cylinder or the other for a purpose which will be made clear presently. As here illustrated, these means comprise a magnet valve V connected between two pipes 70 and 71 which communicate respectively with the opposite ends of the cylinder 11f as shown in Fig. 7. The magnet valve V is of standard construction and comprises, briefly, a valve stem 72 attached to an armature 73 and surrounded by a winding 74. The valve stem 72 is provided at its lower end with a valve member 75 which cooperates with a valve seat 75a, and is biased to an upper position in which the valve member is out of engagement with the valve seat 75a by means of a flat leaf spring 76 interposed between the armature 73 and the upper end of the shell of the magnet. When the winding 74 is deenergized, the valve stem is held in its upper position by the spring 76 and under these conditions fluid can flow freely from one end of the cylinder 11f to the other through the pipes 70 and 71. When, however, the winding 74 is energized, the valve stem moves downwardly to the position in which the valve member 75 engages the seat 75a, and under these conditions pipe 70 is disconnected from pipe 71, so that fluid is prevented from flowing through the pipes 70 and 71. The winding 74 of the valve V is connected with the rails 1 and 1a in series with a battery E (see Fig. 1) in such manner that winding 74

will become energized whenever a train passes over switch A in either direction.

The switch operating apparatus further includes means for locking the switch points in their normal positions for facing point moves over the switch, and for automatically unlocking the points when a train trails the switch. As here illustrated, the locking means comprises a locking plunger 80 adjustably secured at one end to one end of a bolt member 86. The locking plunger 80 is reciprocably mounted for longitudinal sliding movement in suitable guides provided in the auxiliary compartment 11b of the casing 11, and cooperates at the end opposite to the bolt member 86 with a lock rod L which is slidably mounted in the compartment 11b at right angles to the locking plunger. The lock rod L in the form illustrated is of standard construction, and comprises two longitudinally adjustable bars 83 and 84 attached at one end to the front rod 5 of the switch A and provided with registering notches 85 so disposed that these notches will align with the locking plunger 80 when and only when the switch A occupies the extreme position in which it is shown in Fig. 1.

The bolt member 86 at the end opposite to the locking plunger extends with some clearance through a hole 81 provided in the lug 68 on the driving member 18-19, and is provided with a screw jaw 88. The bolt member is surrounded between the lug 68 and a nut 89 which serves as part of the means for adjustably securing the bolt member to the locking member 80, by a compressed coil spring 90 that constantly biases the locking plunger in the direction to cause it to enter the notches 85 in the lock rod L.

For reasons which will become apparent as the description proceeds, the parts of the locking device are so proportioned that when the driving member 18-19 is in its right-hand or normal extreme position in which it is shown in Fig. 2, the biasing spring 90 will tend to drive the locking plunger to an extreme position which is beyond the desired locking position. The locking device is prevented from moving beyond the desired locking position under these conditions, however, by linkage which connects the bolt member 86 with the tie rod 8. As here shown, this linkage includes a slotted link 91 which is connected at one end to the screw jaw 88 by a pin 92. The other end of the link 91 is adjustably connected by means of a turnbuckle 91a (see Fig. 1) with one end of a connecting rod 93, the opposite end of which is pivotally connected with the long arm 94a of a bell crank lever 94. The bell crank lever 94 is pivotally supported in a crank stand 95, and has its short arm 94b pivotally connected with one end of an operating rod 96. The other end of the operating rod 96 is connected with the previously described tie rod 8 by means of a standard switch basket 97. The tie rod 8 may be located at any suitable location, but will preferably be located approximately half-way between the heel and the point of the switch. The base of the crank stand 95 is secured both to a gauge plate 98 and to a tie strap 99 which is fastened at one end to the mechanism B, and it will be apparent, therefore, that any loss of adjustment between the parts due to creepage of the ties is prevented. The slotted link 91, connecting rod 93, bell crank lever 94, operating rod 96, switch basket 97, and tie rod 8 also constitute means for effecting the unlocking of the switch points during a trailing move, as will be made clear presently.

The operation, as a whole, of the portion of the apparatus thus far described is as follows: When the hand throw lever 21 occupies the extreme position in which it is shown in Fig. 2, the driving member 18-19 is held in its extreme right-hand or normal position, as viewed in Fig. 2, and under these conditions the crank 17 is moved toward the right to a position in which the roller 16 carried thereby engages the cam surface 15a on the cam member 15 some distance to the right of the axis of rotation of the cam member. It will be apparent that when the crank 17 occupies this position, any force which is transmitted to it from the spring 31 will act through the cam member 15, the shaft 14 and the arm 14a to exert a force on the movable rails 2 and 2a which urges them to their normal positions in which they are shown in Fig. 1, and the parts are so proportioned that under these conditions the spring 31 will transmit sufficient force to the crank 17 through the spring rod 27, thrust bar 24 and roller 23 to yieldably hold the movable rails in their normal positions. When the movable rails occupy their normal positions, the notches 85 in the lock rod L align with the locking plunger 80, and the locking plunger is therefore moved by the biasing spring 90 to its locking position in which the locking plunger 80 enters the registering notches 85, thus securely locking the switch points in their normal positions.

When it is desired to reverse the switch, the hand throw lever 21 is rotated from the extreme position shown in Fig. 2 to the extreme position shown in Fig. 5. This movement of the hand throw lever causes the driving member 18-19 to move from its extreme right-hand position in which it is shown in Fig. 2 to its extreme left-hand position in which it is shown in Fig. 5. As soon as the driving member 18-19 has moved a relatively short distance in response to this rotation, the lug 68 carried thereby moves into engagement with the screw jaw 88 on the bolt member 86 of the locking device, and as a result, as the driving member continues to move, the locking device is moved with the driving member, thus withdrawing the locking plunger 80 from engagement with the notches 85 in the lock rod L, and hence unlocking the movable rails 2 and 2a. The movement of the driving member will, of course, cause the crank 17 to move toward the left with the driving member, and the parts are so proportioned that while the locking plunger 80 is being withdrawn from engagement with the notches 85 in the lock rod L the roller 16 will continue to engage the cam surface 15a to the right of the pivotal axis of the shaft 14, but that, as soon as the locking plunger has been completely withdrawn from engagement with the notches 85, the roller will move past the pivotal axis of the shaft 14 with the result that during the balance of the movement of the driving member the roller 16 will then engage the cam surface 15a to the left of the pivotal axis. It follows, therefore, that during that portion of the movement of the driving member which is necessary to unlock the movable rails, the spring 31 will continue to bias the movable rails to their normal positions, but that, as soon as the movable rails have become unlocked, the spring 31 will then act to exert on the movable rails a force which causes them to move to their reverse positions. It should be noted that as long as the movable rails remain stationary, the slotted link 91 remains fixed, so that during the first part of the movement of the driving member 18-19, the pin 92 will move out of en-

gagement with the end of the slot in the link. As soon as the movable rails have started to move, however, the resultant movement of the tie rod 8 acting through the switch basket 97, operating rod 96, bell crank lever 94, and the connecting rod 93 causes the slotted link to move in the same direction that the driving member is moving, although the time of motion and the rate of motion of the slotted link will bear no direct relation to the movement of the driving member.

The movement of the driving member 18-19 toward the left, in addition to unlocking the switch and causing the switch rails to reverse in the manner just described, also acts through the lug 68, link 67, and arm 62b to rotate the cam-shaft 62 of the buffering device D in a clockwise direction as viewed in Fig. 8, while the movement of the cam member 15 which takes place while the switch rails are reversing causes the pistons 40 and 41 of the buffering device D to move toward the right. The construction of the cam 62a formed on the cam-shaft 62 is such that during the movement of the switch, valve G of buffering device D is held open until after piston 41 has moved past the left-hand end of leak groove 101, and valve F is opened as soon as piston 40 has reached the right-hand end of leak groove 100. As a result, the movement of the pistons 40 and 41 toward the right under these conditions causes fluid to flow from cylinder 11f on the right-hand side of piston 41 past valve G into reservoir 11g until piston 41 has passed the left-hand end of the leak groove 101 (see Fig. 8), whereupon valve G closes, and fluid in the right-hand side of piston 41 thereafter flows through leak groove 101 into cylinder 11f between pistons 40 and 41. During this movement, fluid also flows from cylinder 11f between pistons 40 and 41 through the leak groove 100 into cylinder 11f on the left-hand side of piston 40 until piston 40 passes the right-hand end of leak groove 100, whereupon valve F opens and fluid then flows from reservoir 11g into cylinder 11f on the left-hand side of piston 40 through valve F. Furthermore, under these conditions, if valve V is deenergized as will normally be the case, fluid is also free to flow from cylinder 11f on the right-hand side of piston 41 through pipes 71 and 70 to cylinder 11f on the left-hand side of pistons 40. It will be apparent, therefore, that during the movement of the movable switch rails from their normal to their reverse positions by the switch operating device B, the fluid in cylinder 11f offers very little resistance to the movement of the pistons 40 and 41, and the buffering device D therefore exerts practically no buffering action on the switch points.

In order to restore the movable rails to their normal positions after they have been reversed as above described, the hand throw lever 21 is restored to the position in which it is shown in full lines in the drawings. The subsequent movements of the parts under these conditions are just the reverse of those described above, and it is believed therefore that the operation of the apparatus under these conditions will be readily understood from an inspection of the drawings without further detailed description.

I shall now assume that the parts are in their normal positions, as shown in the drawings, and that a train trails the switch. As the leading wheels of the train roll along the fixed rail 1 and the movable rail 2a, the movable rails 2 and 2a are forced over laterally, but before a sufficient force is developed to overcome the opposing force exerted by the spring 31 and cause the

point of the movable rail 2 to move out of engagement with the fixed rail 1, the movable rails being somewhat resilient become bent, so that, with the usual standard split switch, the tie rod 8 is moved upwardly as viewed in Fig. 1, three-quarters of an inch or more. This movement of the tie rod acting through the switch basket 97, operating rod 96, bell crank lever 94, connecting rod 93 and slotted link 91 moves the locking device in opposition to the bias of the spring 98 a sufficient amount to withdraw the locking plunger 80 completely out of engagement with the notches 85 in the lock rod L, thus unlocking the switch (see Fig. 4). As a result, when the leading wheels have reached the positions in which a sufficient force is developed to cause the point of the movable rail 2 to move out of engagement with the fixed rail 1, the movable rails will be unlocked, and the movable rails 20 will therefore be forced toward their reverse positions in exactly the same manner as if no point lock were provided. The movement of the movable rails away from their normal positions acts through the head rod 6, tie rod 9, operating arm 14a and shaft 14 to rotate the cam member 15 in a counterclockwise direction to the position shown in Fig. 4, and this latter rotation, in turn, acts through the roller 16, crank 17, roller 23, thrust bar 24 and spring rod 27 to compress the spring 31 beyond its initial compression as shown in Fig. 4, with the result that the spring tends to constantly restore the movable rails to their normal positions. The rotation of the cam member 15 also acts through the arm 15b and piston rod 36 to move the pistons 40 and 41 of buffering device D toward the right in the same manner as was described hereinbefore when the switch was moved from its normal to its reverse position by operation of the hand throw lever 21. However, under these conditions, the driving member 18-19 is held stationary so that valve G is held open during the entire movement of the pistons toward the right, and valve V is energized. As a result, the fluid in cylinder 11f on the right-hand side of piston 41 now flows through valve G into reservoir 11g until piston 41 has moved past the end of leak groove 101, whereupon fluid then flows past piston 41 through leak groove 101. The fluid in cylinder 11f on the right-hand side of piston 40 during this movement flows through leak groove 100 past piston 40 into cylinder 11f on the left-hand side of piston 40 until piston 40 has moved to the end of the leak groove, whereupon the pressure of the fluid in reservoir 11g opens valve F and permits fluid to flow through the ports 44 and 43 into the cylinder 11f on the left-hand side of piston 40. The pressure exerted on the member 45 of valve F by spring 49 is comparatively small so that very little pressure is required to open valve F. It will be apparent, therefore, that the buffering device D offers very little resistance to the movement of the movable rails away from their initial positions under these conditions. As soon as the movable rails start to return to their initial positions due to the bias of spring 31, however, spring 49 closes valve F, so that fluid cannot pass this valve, and since valve V is now energized, and the piston 40 is past the right-hand end of leak groove 100, it will be obvious that the fluid in cylinder 11f on the right-hand side of piston 40 will be trapped in the end of the cylinder. This trapped fluid will prevent any movement of the piston rod 36, and it will be apparent therefore that the buffering device will act to retain the

movable rails in their trailed positions as long as valve V remains energized. Valve V under these conditions will remain energized until the train has completely trailed the switch, whereupon it will become deenergized and will permit the trapped fluid to flow through the pipes 70 and 71 into the right-hand end of cylinder 11f. When this happens, the biasing force due to the spring 31 will then act to restore the movable rails to their normal positions at a relatively rapid rate. When the movable rails have been restored to their full normal positions, all parts will then be restored to their normal positions in which they are shown in Fig. 2.

When the switch occupies its reverse position and a train trails the switch, the movable rails will initially be unlocked, and the movement of the movable rails toward their normal positions will tend to move the parts to the positions in which the movable rails will become locked. However, the movable rails never fully reach the extreme position opposite to their initially set positions when a train trails the switch, and the switch will therefore remain unlocked. The buffering device D under these conditions will function in a manner similar to that in which it functions when the switch occupies its normal position and a train trails the switch, it being noted that under these conditions valve F will be held open and fluid will become trapped in the right-hand end of cylinder 11f to retain the movable rails in their trailed positions. Since this operation is similar to that previously described, it is believed to be unnecessary to describe it in further detail herein.

It should be particularly pointed out that with the mechanism constructed in the manner described there is very little, if any, reaction force transmitted to the hand lever 21 from the biasing spring 31 in the direction to cause rotation of the hand lever, and if there is any reaction force it is so small that it can readily be counterbalanced by the weight of the hand throw lever and the friction in the parts.

It should also be pointed out that by properly shaping the cam member 15a, the force required to move the movable rails of the switch from either extreme position to the other when a train trails the switch can be made to remain substantially constant throughout the switch stroke or to actually decrease as the switch points are moved away from their initially set positions. This is very desirable since it materially decreases wear.

The apparatus will usually also be provided with a circuit controller including means for indicating when the locking device 39 is in its proper locking position for either facing point or trailing moves over the switch in its normal extreme position, and means for indicating when the movable rail which should be in close engagement with the associated fixed rail in either extreme position of the switch is in proper engagement with such fixed rail. This circuit controller is not shown since it is of well-known construction. It is intended, however, to be mounted in the auxiliary compartment 11b, and may for example be similar to that shown and described in Letters Patent of the United States No. 1,976,827, granted to Herbert L. Bone on October 16, 1934, for Railway switch operating apparatus.

Referring now to Figs. 10, 11 and 12, I have here shown a modified form of switch operating mechanism B1 which may be employed in place of the mechanism B shown in the preceding views. The mechanism B1 comprises a main casing 111

provided with a tail-like projection 111a, and an auxiliary casing 112 which is secured to the tail-like projection 111a of the main casing 111. The upper end of the main casing is closed by a cover 111b, while the auxiliary casing is closed by a hinged cover 112a.

A switch actuating shaft 114 is journaled in a vertical bearing 111c provided in the bottom wall of the main casing 111, and is operatively connected at its lower end with the operating rod 9 through the medium of a removable switch operating arm 114a in the same manner that the shaft 14 shown in Figs. 1 to 5 is operatively connected with the operating rod 9.

The upper end of the shaft 114 is provided with a two arm crank 115, the one arm of which carries a roller 116 and the other arm of which carries a roller 117 (see Fig. 14). The roller 116 extends into and cooperates with a cam slot 119a formed in a plate 119 mounted for longitudinal sliding movement in the bottom of the main casing 111, while the roller 117 extends into and cooperates with a cam slot 118a provided on the underside of a plate 118 which is mounted for longitudinal sliding movement in the casing 111 directly above the plate 119. To permit the roller 117 to extend into the cam slot 118a, an opening 119b (Figs. 12 and 14) is formed in the plate 119 through which the arm of the crank 115 which carries the roller 117 extends with considerable clearance. The upper plate 118 is provided on its upper side with rack teeth 120, and is adapted to be reciprocated between two extreme positions by means of a hand throw lever 121 fixed to a shaft 122. The shaft 122 is journaled in suitable bearings provided in the side walls of the main casing 111, and has fixed thereto a segment gear 122a which meshes with the rack teeth 120.

A transversely extending thrust bar 124a is operatively connected with the plate 119 adjacent one end thereof by means of transversely spaced bolts 125 which are secured at one end to the thrust bar and the other ends of which pass through clearance holes in an upstanding rib 119c formed integrally with the plate 119, and a similar thrust bar 124b is similarly operatively connected with the plate 119 adjacent its opposite end. The two thrust bars are biased away from the associated ribs 119c to the extent permitted by the bolts by means of compressed coil springs 126 which surround the bolts 125 between the thrust bars and the ribs, and the thrust bar 124a cooperates with a depending portion 118b formed on one end of the plate 118, while the thrust bar 124b cooperates with a depending portion 118c formed on the other end of the plate 118. The function of the thrust bars will be made clear presently.

The plate 119 is further connected at one end with the piston rod 36 of a buffering device D1. This buffering device is identical in all respects to the buffering device D previously described except for the fact that the pipes 70 and 71 and the valve V connecting the two ends of the cylinder have been omitted and that, as shown in Fig. 13, the left-hand end of the cylinder 11d is connected with the reservoir 11g through a port 130, a regulating valve 131, and two ports 132 and 133, while the right-hand end of the cylinder 11d is connected with the reservoir 11g through a port 134, a regulating valve 135, and two ports 136 and 137.

The regulating valve 131 may have any suitable form, but in the form here shown, this valve com-

prises a cylindrical valve member 131a fitting within a hole 138 in the cylinder head 38 and attached to a valve stem 131b. The valve member 131a is provided with a plurality of restricted orifices 131c, one or more of which may be brought into registry with the port 132 by turning the valve member 131a.

The regulating valve 135 is similar to the regulating valve 131 and comprises a cylindrical valve member 135a fitting in a hole 139 in the cylinder head 37 and attached to a valve stem 135b. The valve member 135a is provided with a plurality of restricted orifices 135c one or more of which may be brought into registry with the port 136 by turning the valve member 135.

The shaft 62 of the device D1 is operatively connected by means of the arm 62a and an adjustable link 67 with a cam follower 141 (see Fig. 15) mounted on an eccentric cam 140 secured to the shaft 122. The parts are so proportioned that when the hand throw lever occupies its normal position in which it is shown in Fig. 11, the valve G will be closed and the valve F will be open, but that when the hand throw lever is reversed, the valve F will be closed and the valve G will be open.

Reciprocably mounted in the casing 111 directly above the plate 118 is a locking device 150 comprising two spaced parallel side members 150a and 150b connected together at their opposite ends by means of integral end members 150c and 150d. The right-hand end member carries a rectangular locking plunger 80, and is formed with two spaced threaded holes 150f and 150g, while the other end member 150d is provided with three unthreaded holes 150h, 150j and 150k, two of which holes 150h and 150k align, respectively, with the threaded holes 150f and 150g. The locking plunger 80 projects with some clearance into a longitudinally extending guideway provided in the tail-like projecting 111a of the casing 111, and cooperates at its inner end with the lock rod L in the same manner as is the case with the apparatus described in connection with Figs. 1 to 5, inclusive. The locking device 150 also comprises two bolt members 150l and 150m which pass through the holes 150h and 150k, respectively, and are screwed into the threaded holes 150f and 150g. These bolt members also extend with some clearance through holes 151 and 152 formed in lugs 153 and 154 secured to the upper face of the plate 118, and surrounding each bolt member between the associated lug 153 or 154 and the end member 150c is a compressed coil spring 150n which biases the locking device in the direction to cause the locking plunger 80 to enter the notches 85 in the lock rod L.

The parts of the locking device are so proportioned that when the plate 118 is in its right-hand or normal position as shown in Figs. 11 and 12, the biasing springs 150n will tend to drive the locking device beyond the desired locking position. The locking device is prevented from moving beyond the desired locking position, under these conditions, however, by linkage which is similar to that employed in Fig. 1 to connect the locking device there shown with the tie rod 8 except for the fact that this linkage includes in place of the slotted link 91 a plunger bolt 155. The plunger 155 extends with some clearance through the hole 150j in the end member 150d, and its head engages the right-hand side of the end member 150d, as viewed in Figs. 3 and 4.

The operation of the apparatus shown in Figs.

10, 11 and 12 is as follows: When the hand throw lever occupies the extreme position in which it is shown in the drawings, the upper plate 118 is held in its extreme right-hand or normal position, and the parts are so proportioned that under these conditions the depending portion 118c on the plate will engage the thrust bar 124b and will thereby compress the springs 126 associated with this thrust bar beyond their initial compression to thus exert a force on the plate 119 which yieldably urges it to an extreme right-hand position. The cam slot 119a in the plate 119 has a radius of curvature equal to the arc through which the roller 116 moves when the shaft 114 is rotated, but 15 is disposed in the plate 119 in such an angular position that when the plate 119 is moved to its right-hand extreme position, the roller will move to the upper end of the cam slot 119a, as viewed in Figs. 11, and 14 and will thus rotate the crank 20 shaft in a clockwise direction to one extreme position. When the crank occupies this clockwise extreme position, the roller 117 on the crank 115 is disposed in the left-hand end of the cam slot 119a, and the parts are so proportioned that under 25 these conditions the force applied to the crank through the cam slot 119a and roller 116 will yieldably hold the movable rails in their normal extreme positions. With the movable rails in their normal extreme positions, the notches 85 in the 30 lock rod L align with the locking plunger 80, and the biasing springs 150n therefore move the locking device 150 to its locking position in which the plunger 80 enters the aligned notches 85 to thereby positively lock the movable rails in their normal extreme positions.

When it is desired to reverse the switch, the hand throw lever is rotated from the extreme position in which it is shown in Fig. 11 to its opposite extreme position. This movement of the 40 lever causes the plate 118 to move from its extreme right-hand or normal position to an extreme left-hand or reverse position. As soon as the plate 118 has moved a short distance, the lugs 153 and 154 carried thereby engage the right-hand side of the end member 150d of the locking device 150, and as a result, as the plate 118 continues to move, the locking device 150 is moved along with the plate 118, thus withdrawing the 50 locking plunger 80 from engagement with the notches 85 in the lock rod L, and hence unlocking the movable rails 2 and 2a. Furthermore, as soon as the motion plate has moved a short distance, the depending portion 118c will move out of engagement with the thrust bar 124b and will thus remove the force applied to the lower plate 119 by the associated springs 126. The parts are 55 so proportioned that while the locking plunger 80 is being withdrawn from the notches 85 in the lock rod L, the roller 117 or the crank 115 will move along a portion of the cam slot 119a which is parallel to the direction of motion of the plate 118, and as long as the roller is moving along this portion of the slot, the crank 115 will remain 60 stationary. It follows, therefore, that during that portion of the motion of the motion plate which is necessary to unlock the movable rails of the switch, no force is exerted on these rails tending to reverse them. As soon, however, as this 65 first part of the movement of the plate 118 has been completed, the roller 117 is then engaged by a curved intermediate portion of the cam slot 119a which causes the crank 115 to be rotated in a counter-clockwise direction, as viewed in Fig. 70 11, and hence causes the movable rails to be 75

moved to their reverse positions. The counter-clockwise rotation of the crank 115 also causes the roller 116 to move from the upper to the lower end of the cam slot 119a and hence causes plate 119 to move from its right-hand extreme position to a left-hand extreme position. During the final portion of the movement of the motion plate to its left-hand extreme position the roller 117 enters another straight portion of the cam slot 118a which is parallel to the direction of motion of the motion plate, and the depending portion 118b moves into engagement with the thrust bar 124a and causes the associated springs 126 to become compressed beyond their initial compression, whereby the plate 119 is yieldably urged into a left-hand or reverse extreme position. This yieldable force applied to the plate 119 acts through the cam slot 119a and roller 116 to exert a force on the crank 115 which biases the switch points to, and yieldably holds them in, their reverse extreme positions. During the movement of the hand throw lever 121 from its normal to its reverse position the camshaft 62 of the buffering device D is actuated to close valve F and open valve G, and during the motion of the lower plate 119 from its normal to its reverse extreme position the pistons 40 and 41 of the buffering device D are moved toward the left. Due, however, to the construction of this device, the device offers substantially no resistance to the movement of the plate 119 under these conditions. It should be noted that as long as the movable rails remain stationary, the plunger bolt 155 remains fixed, so that during the first part of the movement of the motion plate the end member 150d of the locking device 150 will move out of engagement with the head of the plunger bolt. As soon as the movable rails have started to move, however, the resultant movement of the tie rod 8 acting through the linkage which connects the plunger bolt with the tie rod causes the plunger bolt to move in the same direction that the motion plate is moving although the time of motion and rate of motion will bear no direct relation to the movement of the motion plate.

When the movable rails have been moved to their reverse positions in the manner just described, they may be restored to their normal positions by restoring the hand throw lever 121 to the position shown. The subsequent movements of the parts under these conditions are just the reverse of those described above, and it is believed that the operation of the apparatus under these conditions will be readily understood from an inspection of the drawings without further description.

I shall now assume that the parts are in their normal positions, as shown in the drawings, and that a train trails the switch. As the leading wheels of the train roll along the fixed rail 1 and the movable rail 2a, the movable rails 2 and 2a are forced over laterally, but before a sufficient force is developed to overcome the force which yieldably holds the points of the movable rails in their normal positions, the movable rails will become bent intermediate their ends and this bending will act through the linkage connecting the tie rod 8 with the locking device to move the locking device 150 in opposition to the bias of the springs 150n a sufficient amount to withdraw the locking plunger 80 completely out of engagement with the notches 85 in the lock rod L, thus unlocking the switch. As a result, when the leading wheels have reached the positions in which

sufficient force is developed to overcome the force holding the points of the movable rails in their normal positions, the movable rails will be unlocked, with the result that the rails will be forced toward their reverse positions by the wheels in exactly the same manner as if no point lock were provided. The movement of the rails toward their reverse positions will rotate the crank 115 in a counterclockwise direction, as viewed in Fig. 11, and this rotation will act through the roller 116 and cam slot 119a to force the plate 119 toward the left. The motion of the plate 119 toward the left, in turn, will compress the springs 126 associated with the thrust bar 124b beyond their initial compression so that these springs will exert an increased force tending to return the movable rails toward their normal extreme positions. The motion of the plate 119 toward the left will also force the piston rod 136 into the buffering device D. Due to its connection with shaft 122, the camshaft 62 will remain stationary under these conditions and will hold the valve F open and the valve G closed. As a result, the buffering device will offer very little resistance to the movement of the piston rod into the cylinder, but any movement of the piston rod in the opposite direction will be limited to the relatively slow rate at which fluid can flow through the valve 135. It will be seen, therefore, that the buffering device will act to prevent the movable rails from snapping back to their normal positions between the passage of successive pairs of wheels through them. When the train which is trailing the switch has completely passed the switch, the movable rails will slowly return to their normal positions under the bias of the springs 126 associated with the thrust bar 124b, and against the retarding force of the buffering device D. During this return movement of the movable rails there will be no deflections of these rails, and the locking plunger 80 will be moved into engagement with the lock rod L before the movable rails have reached their full normal positions in which the lock rod is in the proper position for the notches 85 in the lock rod L to receive the locking plunger. The springs 150n will therefore become compressed, and will urge the locking plunger into engagement with the side of the lock rod, until the notches 85 move into alignment with the locking plunger, at which time the energy stored in the compressed springs 150n will force the locking plunger into place in the notches, thus restoring the switch to its normal locked condition.

The apparatus shown in Figs. 11 and 12 is intended to be provided with a circuit controller disposed in the auxiliary housing 112 for indicating when the switch occupies its normal position and is properly locked in this position. This circuit controller may be similar to that referred to in connection with the description of Figs. 1 to 5, inclusive.

If a train trails the switch when the switch is reversed, the switch will be unlocked and will remain unlocked, but otherwise the operation of the apparatus will be similar to that just described.

Although I have herein shown and described only two forms of railway switch operating apparatus embodying my invention, it is understood that various changes and modifications may be made therein within the scope of the appended claims without departing from the spirit and scope of my invention.

Having thus described my invention, what I claim is:

1. In combination with a railway switch, a switch actuating shaft rotatable between two extreme positions and operatively connected with said switch for moving said switch between its two extreme positions, a cam member secured to said shaft, a driving member reciprocable between two extreme positions, means for reciprocating said driving member between its two extreme positions, a crank carried by said driving member and provided with a first roller which cooperates with said cam member, a second roller secured to said crank, a thrust bar cooperating with said second roller and supported in such manner that longitudinal movement of said thrust bar in one direction will act through said second roller, said crank and said first roller to exert a force on said cam which urges said shaft to its one or its other extreme position according as said driving member occupies its one or its other extreme position, and spring means connected with said thrust bar and acting to yieldably urge it in said one direction to bias said switch to its one or its other extreme position.

2. In combination with a railway switch, a switch actuating shaft rotatable between two extreme positions and operatively connected with said switch for moving said switch between its two extreme positions, a cam member secured to said shaft, a driving member reciprocable between two extreme positions, means for reciprocating said driving member between its two extreme positions, a crank carried by said driving member and provided with a first roller which cooperates with said cam member, a second roller secured to said crank, a thrust bar cooperating with said second roller and supported in such manner that longitudinal movement of said thrust bar in one direction will act through said second roller, said crank and said first roller to exert a force on said cam which urges said shaft to its one or its other extreme position according as said driving member occupies its one or its other extreme position, spring means connected with said thrust bar and acting to yieldably urge it in said one direction to bias said switch to its one or its other extreme position, locking means for locking said switch in one extreme position, means connected with said driving member for biasing said locking means to a locking position when said driving member is moved to one extreme position and for moving said locking means to an unlocking position when said driving member is moved to its other extreme position, and means mechanically actuated by a train trailing said switch for moving said locking means to its unlocking position.

3. In combination with a railway switch, a switch actuating shaft rotatable between two extreme positions and operatively connected with said switch for moving said switch between its two extreme positions, a cam member secured to said shaft, a driving member reciprocable between two extreme positions, means for reciprocating said driving member between its two extreme positions, a crank carried by said driving member and provided with a first roller which cooperates with said cam member, a second roller secured to said crank, a thrust bar cooperating with said second roller and supported in such manner that longitudinal movement of said thrust bar in one direction will act through said second roller, said crank and said first roller to

exert a force on said cam which urges said shaft to its one or its other extreme position according as said driving member occupies its one or its other extreme position, spring means connected with said thrust bar and acting to yieldably urge it in said one direction to bias said switch to its one or its other extreme position, a buffering device connected with said shaft and effective when a train trails said switch to oppose movement of the shaft by said spring means, and means connected with said driving means to render said buffering device ineffective to oppose actuation of said shaft in response to reciprocation of said driving member.

4. In combination with a railway switch, a switch actuating shaft rotatable between two extreme positions and operatively connected with said switch for moving said switch between its two extreme positions, a cam member secured to said shaft, a driving member reciprocable between two extreme positions, means for reciprocating said driving member between its two extreme positions, a crank carried by said driving member and provided with a first roller which cooperates with said cam member, a second roller secured to said crank, a thrust bar cooperating with said second roller and supported in such manner that longitudinal movement of said thrust bar in one direction will act through said second roller, said crank and said first roller to exert a force on said cam which urges said shaft to its one or its other extreme position according as said driving member occupies its one or its other extreme position, spring means connected with said thrust bar and acting to yieldably urge it in said one direction to bias said switch to its one or its other extreme position, locking means for locking said switch in one extreme position, means connected with said driving member for biasing said locking means to a locking position when said driving member is moved to one extreme position and for moving said locking means to an unlocking position when said driving member is moved to its other extreme position, means mechanically actuated by a train trailing said switch for moving said locking means to its unlocking position, a buffering device connected with said shaft and effective when a train trails said switch to oppose movement of the shaft by said spring means, and means connected with said driving member to render said buffering device ineffective to oppose actuation of said shaft in response to reciprocation of said driving member.

5. In combination with a railway switch, a switch actuating shaft rotatable between two extreme positions and operatively connected with said switch for moving said switch between its two extreme positions, a cam member secured to said shaft, a driving member reciprocable between two extreme positions, means for reciprocating said driving member between its two extreme positions, a crank carried by said driving member and provided with a first roller which cooperates with said cam member, a second roller secured to said crank, a thrust bar cooperating with said second roller and supported in such manner that longitudinal movement of said thrust bar in one direction will act through said second roller, said crank and said first roller to exert a force on said cam which urges said shaft to its one or its other extreme position according as said driving member occupies its one or its other extreme position, spring means connected with said thrust bar and acting to yieldably urge it in said one direction to bias said switch to its one or its other extreme position, buffering means connected with said shaft and effective when a train trails said switch to oppose movement of the shaft by said spring means, and means connected with said driving member to render said buffering device ineffective to oppose actuation of said shaft in response to reciprocation of said driving member.

tion to bias said switch to its one or its other extreme position, a buffing device connected with said shaft and including electrically controlled valve means, said buffing device being effective when said valve means is energized to oppose movement of said shaft by said spring means, and means for energizing said valve means when a train trails said switch.

6. In combination with a railway switch, a switch actuating shaft rotatable between two extreme positions and operatively connected with said switch for moving said switch between its two extreme positions, a cam member secured to said shaft, a driving member reciprocable between two extreme positions, means for reciprocating said driving member between its two extreme positions, a crank carried by said driving member and provided with a first roller which cooperates with said cam member, a second roller secured to said crank, a thrust bar 20 cooperating with said second roller and supported in such manner that longitudinal movement of said thrust bar in one direction will act through said second roller, said crank and said first roller to exert a force on said cam which urges said shaft to its one or its other extreme position according as said driving member occupies its one or its other extreme position, spring means connected with said thrust bar and acting to yieldably urge it in said one direction to bias said switch to its one or its other extreme position, a buffing device connected with said shaft and including electrically controlled valve means, said buffing device being effective when said valve means is energized to oppose movement of said shaft by said spring means, means for energizing said valve means when a train trails said switch, and other means operatively connected with said driving member for rendering said buffing device ineffective to oppose actuation of said shaft in response to operation of said driving member.

7. In combination with a railway switch, a

switch actuating shaft rotatable between two extreme positions and operatively connected with said switch for moving it between its two extreme positions, a cam member secured to said shaft, a driving member manually operable between two extreme positions, a thrust bar movable laterally in opposite directions in response to longitudinal movement in opposite directions, means for biasing said thrust bar to one longitudinal position, and means carried by said driving member and operatively connecting said cam member with said thrust bar to cause said biasing means to act through said thrust bar, said cam means, and said shaft to bias said switch to its one or its other extreme position according as said driving member is moved to its one or its other extreme position.

8. In combination with a railway switch, a switch actuating shaft rotatable between two extreme positions and operatively connected with said switch for moving it between its two extreme positions, a cam member secured to said shaft, a driving member manually operable between two extreme positions, a thrust bar movable laterally in opposite directions in response to longitudinal movement in opposite directions, means for biasing said thrust bar to one longitudinal position, means carried by said driving member and operatively connecting said cam member with said thrust bar to cause said biasing means to act through said thrust bar, said cam means, and said shaft to bias said switch to its one or its other extreme position according as said driving member is moved to its one or its other extreme position, a buffing device connected with said shaft and including electrically controlled valve means, said buffing device being effective when said valve means is energized to oppose movement of said shaft by said spring means, and means for energizing said valve means when a train trails said switch.

GEORGE L. TEMPLE.
